UNITED STATES PATENT OFFICE.

GEORGE KERR ANDERSON, OF PHILADELPHIA, PENNSYLVANIA.

SHORTHAND TYPE-WRITING MACHINE.

1,108,661.

Specification of Letters Patent. Patented Aug. 25, 1914.

Original application filed August 10, 1908, Serial No. 447,749. Divided and this application filed October 23, 1912. Serial No. 727,459.

To all whom it may concern:

Be it known that I, GEORGE KERR ANDERSON, a citizen of the United States, residing in the city and county of Philadelphia, in the Commonwealth of Pennsylvania, have invented certain new and useful Improvements in Shorthand Type-Writing Machines, of which the following is a specification.

10 The object of this invention is to effect certain improvements in the construction and operation of shorthand typewriting machines, hereafter usually spoken of as shorthand typewriters, especially the method of supporting the key-bars and the arrangement of the key-boards, and the invention resides in the novel features of construction and operation set forth in the following specification and claims and illustrated in 15 the annexed drawings, in which—

Figure 1 is a plan view of the machine, showing the arrangement of the keys and key-buttons, the separate mounting of the printing keys and shift keys, the type-frames and part of the feed mechanism and rear portion of the machine. Fig. 2 is a sectional view of the printing keys and shift keys of my machine and means for supporting same, on the line A A of Fig. 1. Fig. 3 is a side view and Fig. 4 a plan view of section of shift key bar, showing tubular bearing and method of attaching same to the key-bar. Fig. 5 is a plan view of the key-board of my machine where code mark keys 25 are substituted for shift keys, and Figs. 6, 30 7 and 8 are detail views showing method of supporting the key-bars.

This application is, in part, a division of my pending application 447,749, filed August 10, 1908, to which reference is made for a fuller description of the workings of the machine as a whole.

On each side of the base of the machine are the upright side plates 1, 1, in which are 35 revolvably mounted the type-frames, 14, on the journal rod, 13, and in which is also mounted the feed frame, 16, on the pivot rod, 15. The three type-frames are provided on the lower side with rows of type as explained in my Patent 581,570, and in my pending application 447,749, and beneath these type-frames are located, side by side, the printing keys, 5, in positions correspond-

ing to the rows of type on the type frames above them, all of which is fully explained in the patent and application for patent just referred to. This explanation is not repeated here because the advantages of arranging the key board of a shorthand machine are not confined to machines where the method of supporting the key-bars or the method of printing would correspond to those described in this application, but would extend and apply to any writing machine wherein a number of keys could be struck simultaneously and the key board of which was adapted to a substantially similar arrangement.

Fig. 1 shows a portion, 17, of the feed-frame, 16, resting on the ends of the printing key-bars, 5. The printing key-bars may, so far as the arrangement of the key-board is concerned, be mounted in a guide block as described in my preceding patents, or in any other suitable way, but in the present instance they are provided with long, tubular bearings or hubs, 3, as shown in Fig. 5, and as also shown in Figs. 6, 7 and 8, fastened to the key-bar by a thin strip of metal, 18, which fits close to the key-bar on both sides and is soldered, riveted or otherwise secured thereto, and through which, beneath the key-bar, a piece of tubing passes and is soldered or otherwise fastened, and through this tube the pivot rod 9, passes as shown in Figs. 1, 5, 7 and 8. The advantage of this arrangement is that the key-bar itself is not weakened by the pivot rod going directly through it, as heretofore, and the size of the pivot rod may be greatly increased, while the bearing secured is very much longer than the thickness of the bar, and especially is this the case when, as shown in Figs. 1 and 5, the key-bars are mounted in more than one row. The pivot rods, 9, are supported by the frame, 8, which is secured to the base of the machine and the ends of which are bent up as shown in Fig. 8; and these pivot rods are held in position laterally by the clamps, 10, at each end of the supporting frame, 8. The type frames are moved to bring the characters in the various rows of type immediately above and opposite the printing keys, by the shift keys, 6, as already described in my pending application 447,749, and in order to shorten the

stroke of the shift keys, they are mounted closer to the operator and farther from the type frames than the printing keys, as shown in Fig. 1, on a pivot rod which supports all of them and is secured in the lugs 2, 2, at each side of the machine. These shift keys are provided with long, tubular bearings beneath them, as shown in Figs. 1, 2, 3 and 4, and similar in construction to the 10 bearings of the printing keys, which have already been explained. In order to allow the free movement of the shift keys without interfering with the printing keys, they are mounted beneath the latter, that is on a lower plane; an arrangement which, as 15 shown in Fig. 1, permits one series of keys to freely cross another series—a very important advantage where space is so limited as in a machine of this character. Only two 20 of the shift keys require springs, and these are provided with spiral springs, 11, as shown in Fig. 1. The figure shift, 7, is so fully described in application 447,749, that only its location will be indicated here, as 25 has been done in Fig. 1. The shift keys are bent as shown in Figs. 2 and 3, to make them high enough to pass over the feed frame, 16, and low enough to be out of the way of the printing keys. The three type frames, 14, 30 are revolvably mounted on the pivot rod, 13, which is secured in the upright side plates, 1, 1, of the machine. These type frames are provided with type as follows:

Left hand type frame—consonants:

35 S Q Z X J,
S M N V K L Y
S P B F G L R
S T D W C H R

40 Central type frame—vowels:

1 2 3
O U I
E A W

45 Right hand type frame—consonants:

4 5 6 7 8 9
L K M F P S
V R N D T S

50 When all the printing keys are struck simultaneously, but no shift keys, the following letters will appear printed across the strip of paper:

55 S T D W C H R E A W V R N D T S

which, referring to the key board, Fig. 1, are the bottom letter on each key button. If the first seven printing keys are struck simultaneously with the left hand shift key, the 60 following letters will be printed:

S P B F G L R

which appear on the key board as the second letters from the bottom of the respective 65 keys. If the same printing keys and the

next shift key are struck simultaneously, they will print the following:

S M N V K L Y

which appear on the key board as the third letters from the bottom of the respective 70 keys. If the same keys are struck simultaneously with both the left hand shift keys, the following characters will be printed:

75 S Q Z X J.,

which appear on the key board as the top letters on their respective keys. If the three vowel keys are struck simultaneously with the shift key marked vowels, on Fig. 13, the 80 following letters will be printed:

O U I

If the six remaining printing keys are struck simultaneously with the right hand 85 consonant shift, they will print

L K M F P S

The shift key for figures operates as explained in my pending application 447,749, 90 and is located between the printing keys and the type frames, to be out of the way of all the keys that are used in spelling words. The central type frame, carrying the vowels, is provided with a long arm, 20, as shown 95 in Fig. 1, the purpose of which is fully explained in my pending application 447,749, and in order to permit the vowel shift key to operate this frame and at the same time have its key button located next to the key 100 buttons of the vowel keys, the end of this shift key is bent so as to come around the end of the adjoining shift key, 6^a, as shown in Fig. 1.

While the letters and characters here 105 shown are the ones recommended, other letters and characters might be used without departing from the spirit of this invention. So also the type might be on complete type 110 wheels similar to those used in other writing machines, instead of on type segments or, as they have been termed, type frames, as here illustrated, or other means well known in the typewriting art or means not yet devised might be used for printing letters 115 without departing from the spirit of this invention, which relates mainly to the arrangement of the keys themselves and to the method of supporting the key-bars when key-bars of the kind herein described are used 120 in connection with the key board here shown.

In a machine of this character, where mind and hand must act in unison several times each second, the arrangement of the 125 key board, the arrangement of the key buttons on the key board, is of the greatest importance, and the arrangement shown in this application is the result of a great deal of study and many practical experiments. 130

The purpose of this arrangement is (1) to assist the mind of the operator to act quickly by locating shift keys operating adjoining groups of printing keys near enough together to be operated by the same finger, if located at the side of the keyboard, or by the same thumb if located in the central portion of the key board and under the thumb; (2) to assist the mind of the operator to act quickly, by putting all the shift keys in a special group and thereby avoid confusion arising from uncertainty as to whether he is striking a shift key or a printing key; (3) to further assist the mind of the operator by locating this special group of shift keys entirely apart from the printing keys and where they can be operated by distinctly different members of the hand—the thumbs, leaving all the fingers to operate all the printing keys; (4) to assist the hand of the operator by locating the shift keys, which are so frequently used, near the center of the key board, where they can be operated by the most active members of the hand; and (5) to assist the mind of the operator by locating each shift key as close as practicable to the group of printing keys in connection with which it is used. While the ideal arrangement of a keyboard is one embodying all these features, as illustrated in the drawings, it is obvious that a key board might be arranged embodying only some of them and securing a part of the advantages herein set forth, without departing from the spirit of this invention; and it is also obvious that the method of supporting the key-bars herein described might be used with an entirely different key board or that this key board might be used with key-bars and printing arrangements of an entirely different character from those herein described, without departing from the spirit of this invention.

Having fully described my invention, what I claim and desire to secure by Letters Patent is,—

1. In a shorthand typewriter a series of printing keys mounted parallel to each other and having their ends resting side by side beneath type-frames provided with type arranged in rows corresponding in number and location to the ends of the key-bars beneath them; said type-frames being moved by a plurality of shift-keys as hereinbefore described said printing keys and shift keys being provided with key-buttons so arranged that all the printing keys can be operated by the fingers and all the shift-keys by the thumbs.

2. In a shorthand typewriter, a type frame provided with vowels, revolubly mounted between other type-frames provided with consonants, a series of printing keys adapted to operate against said type-frames and a shift key for moving said

vowel type-frame, the key-button of said shift-key being located in a separate field from the key-buttons of the printing keys, but in close proximity to the key-buttons of the printing keys which operate in connection with said vowel type-frame. 70

3. In a shorthand typewriter, a type-frame provided with vowels revolubly mounted between other type-frames provided with consonants, printing keys adapted to operate against said type-frames and shift-keys for moving said type-frames, the key button of the vowel shift key being located between the key-buttons of the consonant shift-keys. 75

4. In a shorthand typewriter, a type-frame provided with vowels and a type-frame provided with consonants, said type-frames being revolubly mounted side by side and the characters thereon arranged in a plurality of longitudinal and transverse rows, in combination with shift-keys for moving said type-frames, the key-buttons of said shift-keys being located close enough together for the consonant and vowel shifts 80 to be simultaneously operated by the same finger or thumb. 85

5. In a typewriting machine, a series of printing keys each operating in connection with a plurality of printing characters comprising both vowels and consonants arranged in a plurality of rows and key buttons in pairs, and a series of shift keys operating to vary the characters printed by said printing keys, the key-buttons of the vowel shift-keys and consonant shift-keys being located close enough together to be simultaneously operated by the same finger or thumb, and the vowel shift-key and the consonant shift-key operating independently 90 of each other. 95

6. In a shorthand typewriter, provided with a plurality of printing keys each operating in connection with printing characters, a group of vowel-printing keys located 100 between two groups of consonant-printing keys, and a series of shift-keys adapted to vary the characters printed by the printing keys, the key button of the vowel shift keys being located between the key-buttons of the consonant shift-keys. 115

7. In a typewriting machine a series of printing keys each operating in connection with a plurality of printing characters arranged in the order of a group of vowels between a full alphabet of consonants on the one side and a partial alphabet of consonants on the other, in combination with a series of shift-keys for varying the characters printed by said printing-keys, the key-buttons of the printing-keys being located under the fingers and the key-buttons of the shift-keys being located under the thumbs. 120

8. In a typewriting machine a series of printing keys each operating in connection 125

- with a plurality of printing characters arranged in the order of a group of vowels between a full alphabet of consonants on the one side and a partial alphabet of consonants on the other, in combination with a series of shift-keys for varying the characters printed by said printing keys, the key-buttons of the shift-key operating in connection with the vowel group, and the shift-key operating in connection with the group of consonants composing a partial consonant alphabet, being located close enough together for said shift-keys to be operated by the same finger or thumb. 70
14. In a shorthand typewriter, a series of printing-characters arranged in the order of a group of vowels between two groups of consonants, a series of printing-keys arranged to print simultaneously a plurality of characters from each of said groups and a series of shift keys operating to vary the characters printed by the printing-keys in the several groups, each shift-key operating in connection with the printing characters of its own group independently of any other group, the key-buttons of the shift-keys in adjoining groups being located close enough together to be operated by a single finger or thumb, and the printing-keys being located in pairs, with a space between each pair. 75
15. In a shorthand typewriter, a series of printing-keys each operating in connection with a plurality of printing characters and a series of shift-keys operating to vary the characters printed by said printing-keys, the printing characters being so limited in number and the printing-keys so located that each finger will operate one pair of keys and no more and the shift-keys being located under the thumbs. 80
16. In a shorthand typewriter, a series of printing-keys arranged in pairs, each pair separated from the other by an intervening space and all the printing-keys located under the fingers and each adapted to print a plurality of characters, in combination with a series of shift-keys for varying the characters printed by said printing keys, the key-buttons of the shift-keys being located under the thumbs. 85
17. In a shorthand typewriter, a series of printing characters comprising a group of vowels between two groups of consonants, a series of printing-keys arranged to print simultaneously a plurality of characters from each of said groups, a series of shift-keys operating to vary the characters printed by the printing-keys in their various groups, each shift-key operating in connection with printing characters in one specific group independently of any other group and the key-buttons of the printing-keys being located under the fingers and those of the shift-keys located under the thumbs. 90
18. In a writing machine, a series of key-bars mounted side by side in a plurality of lines on pivot rods properly supported beneath the bars, said bars being provided with hubs of sufficient width to permit the key-bars on one line to pass between those on an adjoining line without coming into contact with them. 95
19. In a shorthand typewriter, a plurality of type-frames, in pivotal connection with supports, a series of printing-keys and a series of shift-keys arranged beneath said printing-keys, the former being arranged in a double row and operable by the fingers and the latter being arranged in a single row and operable by the thumbs, and one of said series of keys operating said type-frames, substantially as described. 100
20. In a shorthand typewriter, a plurality of type-frames pivotally supported and a key-board having a series of printing-keys and a series of shift-keys, the former being arranged in pairs in a double row and the latter being arranged side by side in a single row and beneath the former in crossing relationship and a shift-key for numerals, located between said general key-board and type-frames, substantially as described. 105
21. In a shorthand typewriter, a series of

printing keys having their key-buttons arranged in pairs and operating in connection with a series of printing characters comprising both vowels and consonants arranged in 5 a plurality of rows, in combination with a series of shift-keys operating to vary the characters printed by said printing keys and bring any row of consonants in line with any row of vowels, the key-buttons of the 10 vowel shift-key and the consonant shift-keys being also arranged in pairs and located close enough together to be operated by the same finger or thumb.

20. In a shorthand typewriting machine, 15 a series of printing keys, a feed frame operated thereby and a shift key located above the feed frame and under the printing keys.

21. In a shorthand typewriting machine, 20 a series of printing keys, a feed frame operated thereby and a plurality of shift keys located above the feed frame and having their finger buttons arranged close enough together to be operated simultaneously by the same finger or thumb.

25 22. In a shorthand typewriting machine, a series of printing keys suitably mounted, in combination with a series of shift keys

mounted on either side of said printing keys, the finger buttons of said printing keys being arranged in pairs with an open space 3 between each pair, and the arrangement of the finger buttons of all the keys being such that the printing keys can be operated by the fingers and the shift keys by the thumbs.

23. In a shorthand typewriting machine, 35 a series of printing keys each operating in connection with a plurality of printing characters comprising both vowels and consonants, in combination with a plurality of shift keys adapted to vary the characters printed 40 by said printing keys and mounted at either side of the levers of said printing keys and having their key-buttons located in the central portion of the key-board.

24. In a writing machine, a series of key bars mounted on a plurality of parallel pivot rods beneath them, a frame provided with vertical ends for supporting said pivot rods and a clip for preventing their lateral movement.
